UNITED STATES PATENT OFFICE.

JOHANN GEORG FAHR, OF GOTTMADINGEN, GERMANY, ASSIGNOR TO THE FIRM OF MASCHINENFABRIK FAHR A.-G., OF GOTTMADINGEN, GERMANY.

MOWING-MACHINE.

1,229,248.

Specification of Letters Patent. Patented June 12, 1917.

Application filed October 27, 1914. Serial No. 868,906.

To all whom it may concern:

Be it known that I, JOHANN GEORG FAHR, a citizen of the German Empire, residing at Gottmadingen, in the Grand Duchy of Baden, Germany, have invented certain new and useful Improvements in Mowing-Machines, of which the following is a specification.

My invention relates to improvements in mowing machines, and more particularly in grass mowing machines provided with mechanism for lifting the cutting apparatus and turning the same up in vertical position. In machines of this class in which the cutting apparatus is lifted by the force of the operator the said force is exerted either exclusively by means of a hand operated lever, or during the first part of the lifting movement and into the height of the cut crop by means of a foot operated lever whereupon the rocking movement into upright position is effected by means of a hand operated lever. The object of the improvements is to provide a mowing machine in which the cutting apparatus is lifted and turned up into vertical position by means of the foot of the operator, so that the latter has at all times both hands free for managing the team and for other operations. I am aware that heretofore foot operated levers have been provided in mowing machines for coupling the lifting mechanism of the cutting apparatus with a movable part of the machine, in which case the cutting apparatus is raised by the moving machine and the foot is used only for throwing the said machine into operation for actuating the lifting mechanism. As compared to machines of this type my improved machine is preferable because it is more simple in construction, and because the time which is necessary for lifting the cutting apparatus depends only on the force exerted by the operator and not on the speed of the machine moving over the ground, so that in case of obstacles the cutting apparatus can be lifted more rapidly and the mowing operation must be interrupted only a short distance before the said obstacle.

In my improved machine the foot operated member is so connected with the lifting mechanism that it is not at any time brought out of the reach of the operator or brought in such a position that the oper-

ator can not easily manage the same with his feet, and on the other hand the construction is such that the operator acts with his foot on the lever with sufficient leverage to avoid excessive strain on the foot. For this reason the foot lever is depressed in two successive stages, the foot of the operator performing in both stages the same path. In one embodiment of the invention a special foot lever is provided for each stroke of the lifting mechanism, and in the second embodiment a single foot lever which is returned prior to performing the second stroke into initial position. In both embodiments means are provided for locking the cutting apparatus in an intermediate position, and for returning the foot operated member into operative position after the cutting mechanism has been brought into its lowermost position, even if it has been lowered from an intermediate position.

In order that my invention be more clearly understood two examples embodying the same have been shown in the accompanying drawings, in which the same letters of reference have been used in all the views to indicate corresponding parts. In said drawings—

Figures 1 to 3, are side views of the machine in which two foot levers are provided for operating the lifting mechanism, Fig. 1 showing the lifting mechanism in normal position in which the cutting apparatus is in its lowermost position or in position for mowing, Fig. 2, showing the parts in the intermediate position, and Fig. 3, showing the same in the uppermost or upright position.

Fig. 4, is a plan view of the lifting mechanism shown in Figs. 1 to 3, and

Figs. 5 to 7, are side views similar to those shown in Figs. 1 to 3 and showing the lifting mechanism respectively in the positions in which the cutting mechanism is in the lowermost, the intermediate, and the uppermost or upright positions.

Referring to the example illustrated in Figs. 1 to 4, the cutting apparatus (not shown) may be of any known or preferred construction, such for example as has been shown in the patent of the United States to Johnston and Benjamin, No. 578,404, dated March 9, 1897. It is suspended from an eye 11 of a rocking or lifting lever 12 which is

mounted on the frame 7 of the machine at 10, as is known in the art. The rocking lever 12 is equipped with two operating foot levers 1 and 2, the foot lever 1 being jointed 5 to the rocking lever and the foot lever 2 being rigidly connected thereto. In the normal or mowing position shown in Fig. 1 the foot support of the lever 1 is disposed in position for engagement by the foot of 10 the operator, and it bears on a lug 8 secured to or made integral with the lifting lever 3. By depressing the lifting lever from the position shown in Fig. 1 into the position shown 15 in Fig. 2 the lifting lever is rocked, until a spring latch 4 mounted thereon engages at the rear of a shoulder 5 formed on a relatively fixed part of the machine, so that the lifting lever is locked in an intermediate position in which the cutting mechanism is in 20 the height of the cut crop. By rocking the lifting lever into intermediate position the second foot lever 2 is brought into position for engagement by the foot of the operator, as is shown in Fig. 2. If it is desired to lift 25 the cutting mechanism farther upward and into vertical position, the operator places his foot on the lever 2 and depresses the same so as to rock the lifting lever 3, until the spring latch 4 engages at the rear of a 30 second shoulder 6 formed on the relatively fixed part of the frame 7. During this downward movement the foot lever 1 has not been rocked farther downward, because it is jointed to the lifting lever 3 and is arrested 35 by a fixed part of the frame 7, so that in the end position shown in Fig. 3 the foot lever 2 is located at the side of the foot lever 1 as is shown in dotted lines in Fig. 4.

If the cutting apparatus is allowed to 40 drop on the ground by throwing the spring latch 4 out of locking position by means of the foot lever 9, both foot levers 1 and 2 are returned into initial positions, lever 1 being again lifted from the frame 7 during the second part of the return movement by means 45 of the lug 8. The cutting apparatus can also be dropped directly from its position above the crop by releasing the spring latch 4, whereby both foot levers 1 and 2 are 50 brought from the positions shown in Fig. 2 into the position shown in Fig. 1.

In Figs. 5 to 7 I have shown an example 55 in which a single foot operated lever 17 is provided for lifting the cutting apparatus into upright position. As shown the foot lever 17 is pivotally mounted on a lifting lever 12 which has a rocking support on a pivot bolt 13 secured to the main frame 14. From an eye 15 of the lifting lever the cutting apparatus is suspended, as is known in the art. The foot lever 17 is formed with an arm or extension 22 which engages below 60 a lug 28 formed on the lifting lever 12. To the arm 22 a curved link 27 is connected 65 to which a tension spring 21 is attached. In

the normal position the foot lever is located with its pedal in position for engagement by the foot of the operator. If it is depressed from this position and into the position shown in dotted lines in Fig. 6, it rocks the lifting lever 12 until a spring actuated latch 18 engages in a notch 20 provided on the frame. Thereby the cutting apparatus is locked in position above the cut crop. When being released by the operator the foot lever is returned by the spring 21 into initial position, while the lifting lever remains in locked position. The joint of the link 27 to the arm 22 is thereby brought into the straight line connecting the points *a* 70 and *b*, as is shown in Fig. 6. As the foot lever 17 is thus rocked into initial position the arm 22 is retracted from the lug 28 of the lifting lever and it is brought into engagement with a notch 24 of an arm 23 which is pivotally mounted on the lifting lever. If now the foot lever 17 is again depressed, the lifting lever 12 is further rocked, the 75 rocking movement of the foot lever 17 on the lifting lever being prevented by its engagement with the arm 23. Thus the cutting apparatus is turned up vertically, and it is locked in this position by the spring latch 18 engaging in a notch 25, as is shown in Fig. 7. In this position of the parts the 80 tension of the lifting spring 21 is not sufficient any more to rock the foot lever 17 upward, so that the foot lever remains in its 85 depressed position.

In order to lower the cutting apparatus 90 from upright position downward, the spring latch 18 is thrown out of locking position by depressing the foot lever 19, so that the lifting lever 12 and the pivot bolt of the foot lever 17 are returned into the initial position shown in Fig. 5. By this movement the arm 23 is disengaged from the nose of lever 22, its end being engaged during the return movement of the parts by a stop 26 95 formed on the link 27, so that the nose of lever 22 is released from the notch 24 and bears again in the initial position of the parts on the lug 28.

When lowering the cutting apparatus 100 from its position above the cut crop, after the foot lever 17 has already returned in the manner described into initial position, care must be taken that the foot lever is not carried along and rocked farther upward. When the link 27 returns from the position 105 shown in Fig. 6 into the position shown in Fig. 5, the arm 23 is retracted by the lug 26 from the arm 22. Therefore the arm 22 is again brought into engagement with the stop 28 by the spring 21. Therefore though 110 the pivot bolt of the foot lever 17 moves upward together with the lifting lever 14, yet the foot lever remains substantially in its 115 position by rocking backward on its fulcrum, so that it is in position for being de- 120

pressed in each position which can be assumed by the cutting mechanism for some length of time.

An important feature of the example 5 shown in Figs. 5 to 7 consists in the construction whereby the foot lever after being first depressed automatically returns into initial position in which it is again coupled to the lifting lever, and whereby it is automatically 10 disconnected from the foot lever when the cutting apparatus is moved downward from its position above the cut crop.

While in describing the invention reference has been made to two examples embodying the same, I wish it to be understood that 15 my invention is not limited to the examples shown in the drawings, and that various changes may be made in the general arrangement of the parts and the construction of 20 the details without departing from my invention. For example the mechanism controlling the movement of the foot lever 17 shown in Figs. 5 to 7 may be constructed in a different way.

25 I claim herein as my invention:

1. In a mowing machine, the combination with the frame, the seat of the operator mounted thereon, and the cutting mechanism, of means for lifting the cutting mechanism, and means located in position for 30 operation by the foot of the operator for actuating the lifting mechanism for lifting the cutting mechanism from its lowermost or normal position to its uppermost or upright 35 position, said foot operated means comprising means for locking the lifting mechanism in an intermediate position, a single foot operated member, means for coupling the foot operated member to the lifting mechanism for operation in lifting direction for 40 moving the cutting mechanism first from lowermost or normal position to intermediate position, means operative when the lifting mechanism has been locked in intermediate position to return the foot lever into 45 initial position, and means for again coupling the foot lever to the lifting mechanism for moving the cutting mechanism from intermediate to uppermost position.

50 2. In a mowing machine, the combination with the frame, the seat of the operator mounted thereon, and the cutting mechanism, of mechanism for lifting the cutting mechanism, and means located in position for 55 operation by the foot of the operator for actuating the lifting mechanism for lifting the cutting mechanism from its lowermost or normal position to its uppermost or up-

right position, said foot operated means comprising means for locking the lifting mechanism in an intermediate position, a single foot operated member, means for coupling the foot operated member to the lifting mechanism for operation in lifting direction for moving the cutting mechanism first from lowermost or normal position to intermediate position, means operative when the lifting mechanism has been locked in intermediate position to return the foot lever into initial position, means for again coupling the foot lever to the lifting mechanism for moving the cutting mechanism from intermediate to uppermost position.

3. In a mowing machine, the combination with the frame, the seat of the operator mounted thereon, and the cutting mechanism, of mechanism for lifting the cutting mechanism, and means located in position for operation by the foot of the operator for actuating the lifting mechanism for lifting the cutting mechanism from its lowermost or normal position to its uppermost or upright position, said foot operated means comprising means for locking the lifting mechanism in an intermediate position, a single foot operated lever jointed to the lifting mechanism and having an extension beyond its pivot adapted to engage the lifting mechanism for moving the cutting mechanism from initial or normal position into intermediate position, a spring actuated link jointed to said extension and tending to return the foot operated lever when depressed into initial position, a locking pawl connected with the lifting mechanism and located in position for locking engagement with said extension when the lifting mechanism is in intermediate position, a lug on the link operative when the cutting mechanism is being returned from uppermost or upright position to initial or normal position to throw said pawl out of locking engagement with the extension.

In testimony whereof I affix my signature 110 in presence of two witnesses.

JOHANN GEORG FAHR.
